UNITED STATES PATENT OFFICE

HOWARD H. OETJEN, OF CHICAGO, ILLINOIS, ASSIGNOR TO CHICAGO ELECTRIC MANUFACTURING CO., OF CHICAGO, ILLINOIS, A CORPORATION OF ILLINOIS

ELECTRIC SWITCH

Application filed January 8, 1929. Serial No. 331,116.

My invention relates to electric switches in which the circuit is controlled by the slide-
able movement of a switching member, and
particularly to the class of electric switches
5 in which the switching member moves back
and forth parallel to the front of the switch,
such switches being commonly employed on
flashlights and also for controlling cowl
lamps in automobiles.

10 In its general objects, my invention aims
to provide an unusually inexpensive and
easily assembled switch of this class which
will insure good electrical connections and
which will have a positive snap-over action,
15 and one in which no current is carried by
any flexible or resilient elements.

More particularly, my invention aims to
provide a switch in which the sliding mem-
ber includes an insulating body interposed
20 between a contact plate and a spring mem-
ber, and in which both the contact plate and
spring member interfit the insulating body
so as to be slidably attached to the latter
without requiring auxiliary fastening ele-
25 ments. Furthermore, my invention provides
a switch construction in which a simple
metal punching affords a spring member
serving both for pressing the contact plate
against the terminals of the switch; and in
30 which this spring member cooperates with
formations on a stationary part of the switch
(such as the switch front) to impart a throw-
over movement to the sliding member, and
to latch the latter in either the "on" or the
35 "off" position of the switch. My invention
also aims to provide a compact sliding but-
ton type of switch designed to afford ample
room for a considerable and unrestricted
flexing of the spring member.

40 Still further and also more detailed ob-
jects will appear from the following specifica-
tion and from the accompanying drawings,
in which

45 Fig. 1 is a front view of a switch embody-
ing my invention.

Fig. 2 is an end view of the same, taken
from the right hand of Fig. 1.

50 Fig. 3 is a section taken along the line
3-3 of Fig. 1.

Fig. 4 is a central and longitudinal sec-
tion, taken along the line 4-4 of Fig. 1.

Fig. 5 is a top view of the slide assembly,
and Fig. 6 is a bottom view of the same.

Fig. 7 is an enlarged perspective view 55
of the spring member of the switch.

Fig. 8 is an enlarged perspective view
of the contact member.

Fig. 9 is an enlarged perspective view of
the insulating member of the slide. 60

Fig. 10 is an enlarged perspective view
of the metal frame member of the switch,
which member includes the front plate.

Fig. 11 is an enlarged section taken along
the line 11-11 of Fig. 3. 65

In its immediate commercial application,
the switch of my invention is particularly
suited for use as a cowl-lamp control switch
adapted to have all except its front plate
disposed in a recess bored in the door frame 70
of an automobile, so as to require no cas-
ing for confining the switch parts either
laterally or from their rear. Hence I am
illustrating and describing my switch in an
embodiment suitable for that purpose, al- 75
though I do not wish to be limited in this
respect.

In the illustrated switch, the terminals
comprise two freely spaced terminal brackets
1 and 2, each carrying a wire-clamping screw 80
3. Each of these terminal brackets is se-
cured to the back of an insulating switch
base 4 by a rivet 5 which has its head pro-
jecting slightly forward beyond the switch
base 4, and each of the heads desirably hav- 85
ing its forward face slightly convexed.

The insulating base 4 of the switch also
has two perforations 26 for receiving rear
end fingers 7 respectively carried by two
flat and counterpart wings 8, which wings 90
extend rearwardly at right angles to the metal
front plate 9 with which they are integral.
The wings 8 are wider than the diameters
of the perforations 6 so as to present rear
shoulders 10 abutting against the forward 95
face of the base 4; and the extreme tips
of the fingers 7 are clinched over the rear
of this base, thereby holding the said base
rigidly spaced and parallel to the front plate
9. This front plate 9 has a central aper- 100

ture 11 and along a line centrally transverse of this aperture the front plate has two depressions affording humps 31 directed toward the insulating base 4 of the switch.

Projecting forwardly through the aperture 11 in the front plate is a stem 12 which is fast upon and desirably integral with the insulating body 13 of the sliding member or slide assembly of the switch, this slide body 13 being longer and wider than the button stem but shorter than the aperture 11 in the switch front. The slide body also is considerably thinner than the distance between the front plate 9 and the forward contact faces of the terminal rivets 5; thereby allowing space for a contact plate 14 interposed between the back of the slide body and the terminals 5, and also for a spring member 15 interposed between the front plate 9 and the forward face portions of the slide body.

The contact plate 14 is desirably a metal plate bearing flatwise against the bottom of a recess in the rear face of the slide body 13, and this plate forms the main portion of a movable contact member which also includes an end finger 14A turned up forwardly for engaging one end of the slide body and an opposite end finger 14B extending into a recess 16 in the slide body. The spring member of the switch comprises a metal frame having each longitudinal frame side provided with a forwardly directed hump 15 and having each frame end 17 turned rearwardly and engaging one end of the slide body, each hump 15 being so positioned that it will ride over one of the rearwardly directed humps 31 on the front plate of the switch when the sliding member is moved from one to the other of the two extreme positions respectively shown in Fig. 3 and in Fig. 4. The bore of the frame of the spring member desirably approximates the width of the stem 12 (or actuating portion) of the slide member, so that the side walls of the stem will engage the longitudinal walls of the said bore to prevent the spring member from sliding laterally of the insulating body.

The rear face portion of the slide body against which the contact plate 14 bears is offset forwardly from the end portion 18 of the same face by a distance corresponding to the thickness of the contact plate, so that this face portion 18 is in the same plane with the lower face of the contact plate. To prevent a movement of the contact member on the insulating body transversely of the direction in which the latter slides, I preferably make both the contact plate and the said offset rear face portion of the insulating body narrower than the insulating body, thereby leaving the contact plate laterally housed by a recess which extends to the end of the insulating body adjacent to the finger 14A and from which into the recess 16 opens.

The various switch parts are so proportioned that when the sliding member is in its "on" or circuit-closing position of Fig. 3, the humps 31 on the front plate exert a cam action on the humps 15 of the spring member and press the left-hand end of the stem 12 against the adjacent end of the perforation 11 in the front plate, while the contact plate 14 engages the forward faces of both of the terminals 6.

When the sliding member is moved toward the right from its position in Fig. 3, the humps 31 on the front plate flex the longitudinal sides of the spring member downwardly (or rearwardly of the switch) until the forward spring humps 15 ride over the said front plate humps 31, after which a similar cam action insures a completion of the sliding movement, so as to halt the sliding member when the right-hand end of the stem 12 engages the right-hand end of the perforation 11 in the front plate. This leaves the sliding member in the "off" position shown in Fig. 4, in which the contact plate 14 engages only one of the terminals 6 while the other terminal engages the rear (or lower in Fig. 4) end face portion 18 of the insulating slide body.

To allow for a considerable rearward flexing of the longitudinal members of the frame-like spring without requiring a wide spacing of the insulating body of the slide from the front plate of the switch, I desirably recess the forward face portions 13A of this insulating body which are disposed respectively behind the said longitudinal spring portions and at opposite sides of the stem 12, as for example, by curvedly recessing them as shown in Fig. 9. I also provide each end of the insulating slide body 13 with an extension 19 affording a forwardly directed shoulder 19 disposed for engaging the rear edge of one of the spring frame ends 20. Each such shoulder is disposed so as to hold the adjacent ends of the longitudinal spring frame sides freely spaced from the insulating body, thereby permitting a free flexing of these longitudinal spring sides about their junctures with the spring frame ends 20, and one of these extensions 19 desirably has an end notch 29 into which the finger 14A of the contact member extends.

Furthermore, I desirably form each longitudinal spring frame side 15 to form two consecutive V-shaped parts, thereby providing two rearwardly directed bends 21 connected by the parts which form the forwardly directed hump 15. Such a forming of the frame-like spring permits a free and considerable flexing of each of its longitudinal sides, thereby insuring a quick snap-over action, together with a continuous and firm rearward pressure on the insulating slide body and through the latter on the contact plate which

forms the main part of the movable conducting member of the switch.

In assembling the switch, the spring member of Fig. 7 is slipped down over the stem 12 on the insulator of Fig. 9 until the lower edges of the spring ends abut against the upper faces of the projections 19, and the movable contact member (of Fig. 8) is slidably attached to the insulator from the bottom of the latter, thus completing the assembly of the sliding member of the switch. This sliding member is then inserted in the stationary frame member (Fig. 10) of the switch from the bottom of Fig. 10, with the stem 12 projecting through the perforation 11. Then the insulating base 5 (to which the terminal brackets have previously been riveted, so as to form the assembly shown in Fig. 11) is slipped upward under the sliding member until the fingers 7 on the stationary switch frame extend through the perforations 6 in the base 5, after which these fingers are clinched over to clamp the base against the end shoulders 10 of the wings 8 on the stationary frame member of the switch.

In practice, I desirably make the frontal perforation 11 only slightly wider than the stem 12, so that the longitudinal walls of this perforation will guide the stem and hence the entire sliding member. By doing this and by making the offset rear face portion of the insulating body of a width corresponding to that of the contact plate (as shown in Fig. 6), I hold all parts of the sliding member against relative movement transverse of each other and of the stationary structure which consists of the metal frame of Fig. 10 and the insulating base 6. Consequently, I eliminate the need of auxiliary guide or fastening members.

However, I do not wish to be limited to the details of the construction and arrangement above described, since changes might obviously be made without departing either from the spirit of my invention or from the appended claims.

I claim as my invention:

1. An electric switch, a stationary structure including a wall and a terminal spaced from the wall, a movable switching member interposed between the said wall and terminal; and means associated with the stationary structure for guiding the movable switching member to permit limited reciprocating movement of the latter; the movable switching member comprising an insulator, a contact fitted upon one face of the insulator and movable into and out of engagement with the terminal, and a spring member fitted upon the opposite face of the insulator and continuously pressing the insulator away from the said wall, the contact member and the spring member being slidably attached to the insulator from opposite sides of the insulator.

2. An electric switch, a stationary structure including a wall and a terminal spaced from the wall, a movable switching member interposed between the said wall and terminal; and means associated with the stationary structure for guiding the movable switching member to permit limited reciprocating movement of the latter; the movable switching member comprising an insulator, a contact fitted upon one face of the insulator and movable into and out of engagement with the terminal, and a spring member pressing the insulator away from the said wall, the spring member and the said wall having opposed hump formations adapted to ride over each other during the movement of the sliding member in each direction.

3. An electric switch as per claim 2, in which the insulator has a recess facing the hump formation on the spring member, into which recess the spring is flexed when the said hump formations ride over each other.

4. An electric switch, a stationary structure including a wall and a terminal spaced from the wall, a movable switching member interposed between the said wall and terminal; and means associated with the stationary structure for guiding the movable switching member to permit limited reciprocating movement of the latter; the movable switching member comprising an insulator, a contact fitted upon one face of the insulator and movable into and out of engagement with the terminal, and a spring member fitted upon the opposite face of the insulator and continuously pressing the insulator away from the said wall, the insulator having a face portion flush with the outer face of the contact member and disposed for engaging the contact member when the latter is out of engagement with the terminal.

5. An electric switch comprising a front plate provided with a perforation having parallel opposite edges, a base disposed behind and parallel to the front plate, means rigidly spacing the front plate from the said base; a reciprocable sliding member comprising an insulator disposed between the front plate and the said base and having a stem projecting forwardly through the perforation and laterally guided by the said perforation edges; cooperating contact members respectively mounted on the rear of the sliding member and on the forward face of the said base; a spring member slidably attached to the insulator from the front of the latter and bowed toward the front plate and continuously pressing forwardly against the rear face of the front plate to press the sliding member rearwardly; and means associated with the front plate for limiting the reciprocal movement of the sliding member in each direction.

6. An electric switch as per claim 5, in which the front plate has a rearwardly con-

vexed hump and in which the spring member has a forwardly convexed hump disposed for riding over the aforesaid during the movement of the sliding member in each direction.

5 7. An electric switch as per claim 5, in which the front plate has a rearwardly convexed hump adjacent to one of the said perforation edges, and in which the spring member comprises a frame through which the 10 stem portion of the insulator extends, one leg of the frame having intermediate its ends a hump convexed toward the front plate and adapted to ride over the first named hump when the sliding member is moved with respect to the front plate lengthwise of that frame leg.

8. An electric switch as per claim 5, in which the front plate and the spring member have formations interengaged during a 20 medial portion of the movement of the sliding member for causing the spring member to complete such movement.

9. An electric switch as per claim 5, in which the spring member comprises a frame 25 fitted over the said stem and having two longitudinal frame sides extending parallel to the longitudinal edges of the perforation, each of these frame sides having a medial forwardly directed hump, the front plate 30 having at each side of its said perforation a rearwardly directed hump over which one of the humps on the spring rides when the slide is moved longitudinally of the perforation, the frame having its end sides bent rearwardly and respectively engaging end face 35 portions of the slide body.

10. An electric switch as per claim 5, in which the spring member comprises a frame fitted over the said stem and having two 40 longitudinal frame sides extending parallel to the longitudinal edges of the perforation, each of these frame sides having a medial forwardly directed hump, the front plate having at each side of its said perforation a 45 rearwardly directed hump over which one of the humps on the spring member rides when the slide is moved longitudinally of the perforation, the slide body having its front recessed at each side of the stem to permit a 50 rearward flexing of the adjacent frame side of the spring.

11. In an electric switch, a reciprocating member comprising an insulator, a contact plate mounted on the rear face of the insulator, and a frame-like spring slidably fitted 55 upon the insulator from the front of the latter, the frame-like spring having the end members of its frame respectively engaging the ends of the insulator and the insulator 60 having shoulders respectively engaged by the rear edges of the said end members of the spring, the said shoulders being so disposed as to hold the side members of the frame-like spring out of contact with the forward face 65 of the insulator.

12. A sliding member for an electric switch, as per claim 11, in which each side member of the spring is bent to form two rearwardly directed humps spaced longitudinally of the side members and connected by a bend affording a forwardly directed hump between the 70 said rearwardly directed humps.

13. A sliding member for an electric switch, comprising an insulator having in its rear face a recess spaced from one end of the insulator and reaching to the other end of the insulator; and a contact member comprising a contact plate bearing flatwise against the bottom of the recess and corresponding in thickness to the depth of the recess, and two forwardly directed arms at the ends of the contact plate, one of the said arms being socketed in the recess and the other bearing against the first named end of the insulator. 75

14. A sliding member for an electric switch, as per claim 13, in which the contact plate has its longitudinal edges engaged by walls of the said recess to prevent movement of the contact member or transversely of the insulator. 80

15. In an electric switch, a housing structure including a front and also including two relatively insulated and relatively spaced terminals presenting forward faces behind the front, and a sliding member slidably guided by the housing structure for movement longitudinally of the sliding member and parallel to the front, the terminals being spaced longitudinally of the sliding member; the sliding member including an insulator disposed between said front and both of the said terminal faces, a contact member mounted on the insulator and exposed on the rear face of the insulator, and a spring mounted on the insulator and continuously engaging the rear face of the front to press the insulator rearwardly; the sliding member and the housing structure having interengaging portions disposed for limiting the sliding movement of the sliding member to two extreme positions in one of which the contact member engages both of the said terminal faces, and in the other of which the contact member is out of engagement with one of the terminal faces; the said front and the spring member having continuously engaged formations for causing a rearward flexing of the spring during the movement of the sliding member from one of its said extreme positions toward the other and, for normally holding the said interengaged movement limiting portions of the sliding member and the housing structure interengaged. 90

110 Signed at Chicago, Illinois, December 27th, 1928. 115
